UNITED STATES PATENT OFFICE.

MYRON COLONEY, OF ST. LOUIS, MISSOURI, ASSIGNOR TO JAMES HENRY
MCLEAN, OF SAME PLACE.

TIME-FIRING MECHANISM FOR SHELLS, TORPEDOES, &c.

SPECIFICATION forming part of Letters Patent No. 225,460, dated March 16, 1880.

Application filed November 23, 1878.

To all whom it may concern:

Be it known that I, MYRON COLONEY, of the city and county of St. Louis, and State of Missouri, have invented a Time-Firing Mechanism for Shells, Torpedoes, and Blasting-Cartridges, of which the following is a specification.

My apparatus consists, essentially, of a train of gearing driven by a spring and connected with a suitable governor, preferably a fan, and with a spring firing-pin, which is released by the time mechanism after a period which may be varied by the adjustment of a rotary detent carried by the said time mechanism.

15. In the accompanying drawings, Figure 1 is a side elevation of my time mechanism as adapted for use in explosive projectiles. Fig. 2 is a rear view. Fig. 3 is a transverse section on the line 3 3, looking forward. Fig. 4 is a transverse section on the line 4 4, looking backward. Fig. 5 is a transverse section on the line 5 5, looking forward. Fig. 6 is a longitudinal sectional diagram or flat projection of the mechanism on the broken line 6 6, Fig. 4.

20. The object of this piece of mechanism is to effect and regulate the explosion of gunpowder, gun-cotton, and similar detonating compounds, whether they be used in land or naval warfare or in the industrial arts of blasting or mining. It is especially adapted to the explosion of bomb-shells and torpedoes.

Among its important advantages are the accuracy and simplicity with which it may be timed, and the rapidity in which it may be adjusted and set in motion ready for action; also, the perfect safety from all danger of accident by premature explosion when the use of the mechanism is not needed, and the certainty that it will do its duty at the time required.

By simply removing a small plug, (which protects from tampering,) adjusting the movement to the time required, as indicated on a dial on the rear end, drawing out a small wire which sets the mechanism in motion, and replacing the plug again, the apparatus is set in action, and the explosion will take place at the time required.

50. The whole operation, which is the work of

a few seconds, is done with a small wrench, which the operator holds in his hand.

The mechanism may be constructed so as to run for several hours, or an explosion can be effected immediately, as required. It can 55 be reduced in size to the diameter of a lady's watch by about three inches in length, and by reason of its great strength and lightness and the peculiarity of its construction it can be used in the smallest-size bomb-shells.

60. The following is a detailed description of its parts. The connections will be understood by reference to the flat longitudinal sectional diagram, Fig. 6, in addition to the transverse sections.

65. O is the main arbor, which is operated by the large convolute spring A, and which is wound up by a wrench placed upon the outer end, a. The spring has nearly the whole diameter of the movement to operate in, deducting only the cartridge-holder x and the pillars b b from the entire diameter. The outer end of the spring is secured by one of the pillars, or by a special screw, as shown at d in Fig. 5, and the inner end is held by a pin, which 70 passes transversely through the arbor O and through a hole in the spring.

75. e is a ratchet, which operates the main wheel f. g is a washer, which is held in position by the end of the bearing on the arbor O being riveted over on the outside of the washer at i. The wheel f imparts motion to the pinion h, and thence, through the train of wheels and pinions on the arbors 1 2 3 4 5 6, to the fly j.

80. The train, in the present instance, is geared up in the proportion of twenty-two thousand eight hundred on the fly-shaft to one on the main arbor O. The fly makes in all one hundred and thirty-six thousand eight hundred revolutions to one of the firing-arbor 8, as the 85 main arbor O is geared with the firing-arbor 8 in the proportion of six to one. In other words, when the movement is set so as to make the greatest length of time, as it is at present geared, the fly-arbor must revolve one hundred and thirty-six thousand eight hundred times before the cartridge is fired. The fly 90 passes through the plate c in order that it may have the greatest possible size in the least space.

Motion is given through the arbor 7 to the arbor 8 by the pinion l , which is on the main arbor 0, gearing with the wheel l' on shaft 7, and the pinion m' on shaft 7, gearing with 5 wheel m on shaft 8. The wheel m , through the ratchet o and arbor 8, operates the firing-wheel p . The wheel m being held in the same way as wheel f , the ratchet o allows the arbor s to be turned independently from the outside 10 end, g , and consequently timed at pleasure.

As the firing-wheel draws the trigger s upon every complete revolution, and at the same point, when the movement is set to run its greatest length of time, turning the firing-pin 15 toward the firing-point from the end g , or, in other words, adjusting it, has the effect of reducing the time it will take the movement to bring the pin to the firing-point; and the time necessary to make the entire revolution 20 being already known, the amount of time thus cut off is deducted, and the time of the explosion thereby determined. It must not be inferred, however, that any mathematical calculation is necessary on the part of the operator, 25 as he simply turns the shaft q until the index points to the proper figure on the dial, or he turns a little pointer on his wrench to a secret figure, which to him indicates the time of the explosion, then removes his wrench, and all is 30 ready.

The stud r draws the trigger s (see Figs. 3 and 6) by operating on the incline a' , which liberates the hammer t at u . The hammer thus liberated is thrown forcibly by the spiral spring u upon the cartridge w , and causes its 35 explosion, which, in turn, communicates fire with the compound to be exploded, and the explosion sought for is thereby attained. The hammer is refracted or cocked by means of a 40 thumb-piece, k . The surface p^x of trigger s , coming in contact with the periphery of the firing-wheel p , prevents the liberation of the hammer at u until the recess p' in the firing-wheel p comes opposite to p^x , thereby insuring 45 perfect safety from accident by premature explosion, as the hammer is by this arrangement locked at u by the trigger s .

On the other hand, when the recess p' comes 50 opposite to end p^x of trigger s the trigger-pin r , operated by the spring A through the wheel l , presses against the incline at a' , which draws the trigger, by a positive motion, away from the hammer at u and into the recess p' , thereby insuring the explosion, as before mentioned. 55

The cartridge-holder x is held in position by the pillar b' , Figs. 1, 3, and 5, and by being fitted into the plate c' at g' , as x swings around out of its seat at g , (the hole being cut in the 60 plate to admit of it,) the holder x can be loaded and reloaded at will.

The resisting-piece z serves as a backing to the cartridge w , and also a guide for one end

of the hammer, and is held in position by being screwed up to a shoulder in the plate c . 65

The plates $c' c^2 c^3 c^4$ are held together by the screws $b b$, which screw into the lower plate, and having the heads countersunk into the upper plate. The threaded ends of the screws are finally riveted on the outside, thereby 70 combining a rivet with a screw.

The plates are kept apart and in position by pieces of brass tubing, cut the proper length, through which the screws pass. The tubing and the screws together make the pillars. 75

The movement is set in motion by removing a wire pin, W , Fig. 1, which passes through the plates and some of the main wheels, which effectively lock the movement until it is to be 80 used.

In all the arbors the ratchets, pinions, collets, or seats for the wheels and the pivots are turned and cut in one piece of steel. The wheels are also keyed and riveted on the collets, thereby preventing any stepping of wheels or shifting on arbors, and precluding all possibility of a premature explosion—an event which might occur with the use of the ordinary clock machinery. 90

The clicks or detents are kept in position by tempered-steel springs fastened in such a manner as to remove all liability of shifting.

The principle of the fly is used because it is the simplest, most direct, and positive of any 95 regulator that can be selected, friction being the only element necessary to overcome.

While escapements are more accurate and better adapted to time-pieces than the fly, the fact that they have dead-centers, reciprocating motion, and must be suspended so very delicately renders them useless for such a piece of mechanism as this. 100

The whole movement is constructed with the design of having the greatest strength 105 with the least weight and the largest machinery in the least possible space, and of standing a great shock or concussion without derangement.

Having thus described my invention, the 110 following is what I claim as new therein, and desire to secure by Letters Patent:

1. The combination of the spring pin or hammer t , the trigger s , and the adjustable setting-wheel p , recessed at p' to permit the 115 retraction of the said trigger, and provided with a pin or tappet, r , to retract it.

2. The combination of the spring pin or hammer t , the socket Z , and the eccentrically-pivoted cartridge-receiver x , as and for the 120 purposes set forth.

MYRON COLONEY.
